UNITED STATES PATENT OFFICE.

HENRY B. BRADFORD, OF EDGEMOOR, DELAWARE, ASSIGNOR TO EDGE MOOR IRON COMPANY, OF EDGEMOOR, DELAWARE, A CORPORATION OF DELAWARE.

WATER-TUBE BOILER.

1,069,105.

Specification of Letters Patent.

Patented Aug. 5, 1913.

Application filed September 10, 1912. Serial No. 719,515.

To all whom it may concern:

Be it known that I, HENRY B. BRADFORD, a citizen of the United States, residing in Edgemoor, Brandywine Hundred, New-
5 castle county, State of Delaware, have invented a certain new and useful Improvement in Water-Tube Boilers, of which the following is a true and exact description, reference being had to the accompanying
10 drawings, which form a part thereof.

My present invention relates to water tube boilers and has for its object the provision of simple, durable and effective means for cleaning the outer surfaces of the water tubes with jets of compressed air, or preferably steam, discharged from jet apparatus which is incorporated in and forms a permanent part of the boiler structure. In the preferred construction illustrated, some or
15 20 all of the jet nozzles and portions of the supply piping therefor, are incorporated in the baffle or division walls employed to direct the flow of the gaseous products of combustion from the furnace of the boiler.

25 The various features of novelty which characterize my invention are pointed out with particularity in the claims annexed to and forming a part of this specification. For a better understanding of the invention, 30 however, and of the advantages possessed by it, reference should be had to the accompanying drawings and descriptive matter in which I have illustrated, and described detailed forms in which the invention may
35 be embodied.

Of the drawings: Figure 1 is a longitudinal sectional elevation of a water tube boiler of familiar type, equipped with a preferred form of my improved cleaning apparatus. 40 Fig. 2 is a partial sectional elevation taken on the line 2—2 of Fig. 1 with parts of the division wall broken away and removed to facilitate an understanding of the division wall construction. Fig. 3 is a sectional elevation taken on the line 3—3 of Fig. 2. Fig. 4 is a partial sectional elevation taken on the line 4—4 of Fig. 1. Fig. 5 is a partial sectional elevation taken similarly to Fig. 1, showing a modified construction. Fig. 6 is 45 a partial section taken on the line 6—6 of Fig. 5. Fig. 7 is a partial sectional plan taken on the line 7—7 of Fig. 6.

In the drawings, and referring first to the construction shown in Figs. 1 to 4 inclusive,
50 A and B represent the front and rear head-

ers of a water tube boiler. These headers are connected by a bank of water tubes C which are slightly inclined to the horizontal. Above the bank of water tubes C are located the steam and water drum or drums D which connect the upper ends of the headers. E, E, represent the end walls of the boiler housing, and F, F, represent the side walls of the boiler housing. G represents the bridge wall located beneath the water tubes at the rear end of the furnace chamber, and H and I represent baffle or division walls employed to cause the gaseous products of combustion, issuing from the furnace chamber, to pass upward through the intertube space adjacent the front header A, then downward through an intermediate portion of the intertube space, and upward through the portion of the intertube space adjacent the rear header. In so far as above described the boiler construction is of a type which is well-known and in general use. The division wall H, which rises from the bridge wall G, comprises, in the preferred construction illustrated, a skeleton frame work which is incorporated in and reinforces a body of suitable refractory material which may advantageously be composed of the material commercially known as hot blast cement. This cement is highly refractory, and possesses considerable mechanical strength due in part to an asbestos fiber incorporated in it.

As shown best in Figs. 2 and 3, the skeleton frame work of the division wall H comprises a parallel series of wrought metal angle bars J, which are parallel to each other, and are inclined to the horizontal to correspond to the arrangement of water tubes C, which are so disposed that appreciable spaces exist between inclined rows of the water tubes, whereas no such spaces exist between horizontal and vertical rows of the tubes. This arrangement of the water tubes is made desirable in certain types of boilers by considerations which have nothing to do with the cleaning provisions or division wall construction employed herein. The skeleton frame work also comprises a second set of wrought metal angle bars JA, which are parallel to each other, and lie between the rows of tube C which extend transversely to, though, as shown, not exactly perpendicular to the rows of tubes between which the bars J are located. The

angle bars J and JA are arranged so that their flanges J' extend transversely to the tubes C and abut against each other, while the flanges J² of the bars J and JA extend 5 toward the front and rear headers respectively of the boiler. The bars J and JA are connected together at appropriate points as by rivets or bolts J³. The ends of the bars J and JA adjacent the side walls, F, F, 10 of the housing are secured to vertical bars J⁴. To more effectually protect the lower ends of the wrought metal bars J and JA from the high temperatures prevailing in the lower portions of the first pass for the 15 hot gaseous products, cast metal sections K are employed. One of these sections is inserted between each pair of inclined rows of tubes C between which is also located a corresponding angle bar JA. Each section 20 K is notched at its opposite edges to receive the corresponding water tubes and may be inserted after the tubes C are put in place by first passing it between the tubes with the plane of the section parallel to the length of 25 the tubes, and then giving it a quarter turn about its longitudinal axis. Each adjacent pair of sections K meet in the spaces between the tubes of the row engaged in part by each section. The cast iron sections may 30 be connected together at various points by means of bolts or pins K'. The division wall I may be substantially identical in construction with the division wall H, except that, the cast metal sections K, are unnecessary and are omitted in the case of the 35 wall I.

The novel provisions which I make for removing soot, ashes or the like accumulating on the outer surfaces of the water 40 tubes C comprise a series of jet nozzles O and O' and supply pipes M therefor which are incorporated in the division wall H. The pipes M are parallel to the angle bars JA and are similarly arranged 45 between the inclined rows of water tubes C, though as shown, each adjacent pair of parallel pipes M are separated by two rows of water tubes. Such of the pipes M as have their lower ends 50 terminating below the water tubes are connected by pipe connections M' to a pipe N which extends transversely to, and beneath the bank of tubes C on the rear side of the division wall H, and may rest on and be 55 supported by a portion of the bridge wall G. The inner closed end of the pipe N is received in the recess F' formed in one side wall F of the boiler housing, while the other end of the pipe passes through the other 60 side wall F, and is externally connected to the steam space of the boiler or to some other source of pressure fluid through a regulating valve N² which may be a simple gate or throttle valve. Such of the pipes M, 65 as have their lower ends terminating at the

side of the bank of tubes C are connected to a vertical branch pipe N' which is located in a recess F² formed in the corresponding side wall of the boiler housing, and is connected at its lower end to the pipe N. The nozzles O and O', connected to the pipes M at suitable points along the length of the latter, extend parallel to tubes C and point toward the front header A. As shown in Fig. 3 these nozzles, which may be formed of heavy wrought iron are of such length that they project slightly from the front wall of the body portion of the division wall. The only difference between the nozzles O and O' is that the nozzles O' which project through the sections K are longer than the nozzles O to correspond to the increased thickness of the lower portion of the division wall H.

P represents a drain pipe connected to the pipe N and provided with a controlling valve P'. The pipe P and pipe P' serve to drain off the water of condensation formed in the piping N, N', M' and M when steam is the jet cleaning fluid employed, and also to permit atmospheric air to be drawn into this piping when the steam supply valve N² is closed and the subsequent condensation of steam tends to create a vacuum in the piping. The free admission of atmospheric air to this tube prevents the furnace gases being sucked into the piping through the nozzle orifices. The admission of such gases is objectionable, because of their corroding effect on the pipes. In operation it will be understood that the valve P' is opened, when the valve N² is closed, and is closed when the valve N² is opened.

The division wall I may have cleaning provisions incorporated in it exactly similar to those incorporated in the division wall H, but advantageously as shown, the main transverse supply pipe NA, corresponding in function to the pipe N, is arranged above and rests on the top row of tubes C. The pipes MA, corresponding generally otherwise to the pipes M, are connected at their upper ends to the pipe NA, or to the depending lateral branch NA' thereof, have their lower ends closed by the caps M² and are arranged parallel to the bars J, and not to the bars JA. The drain and pressure equalizing pipe PA is connected to the lower end of the branch pipe NA', and is controlled exterior of the boiler housing by the valve PA'. The nozzles O, connected to the pipes NA are similar in construction and arrangement to the nozzles O incorporated in the division wall H, and like the latter in the particular construction illustrated point toward the front header A. In the division wall I the pipes MA are arranged in front of the bars JA so that the reactive thrust of the jets is transmitted directly to the skeleton frame work of the division wall, and the

5 pipes MA need not be secured to the skeleton frame work, except lightly, in assembling them as by wiring them to the wrought metal skeleton frame work. In the case of the division wall H however, on account of the relatively high temperature of the gaseous products of combustion traversing the first pass of the intertube space, I prefer to arrange the tubes M back of the angle bars 10 J, and, in this case, I anchor the pipes M to the angle bars JA as by means of the U bolts M³, shown in Figs. 2 and 3.

15 Immediately in front of the rear header B, I place a series of pipes MB, which with their nozzles O and connections MB', and NB, NB', NB², PB, and PB'; are similar in construction and arranged to the parts MA, MA', NA, NA', NA², PA, and PA', already described. The cleaning provisions immediately in front of the rear header, however, are not embedded in cement, but are directly exposed to the gaseous products of combustion. The lower temperatures of the latter, however, when traversing the final pass of 25 the intertube space, makes this direct exposure unobjectionable. The pipes MB' may be lightly secured in place as by wiring them to the tubes C, or to the rear header B.

30 The operation of the cleaning apparatus described will be fairly apparent from the foregoing description. Each of the three passes into which the intertube space is divided, is provided with separate cleaning provisions, ordinarily operated separately.

35 An important feature of the simple construction illustrated is that both the main transversing steam supply pipe, and the inclined pipes to which the nozzles are directly connected, may be large enough in 40 cross section so that the pressure of discharge will be the same at each nozzle. This means in general that the cross section of each supply pipe at any portion of the latter shall be equal to, or exceed the aggregate 45 area of the nozzle orifices receiving steam through said portion of the supply pipe. This inherent capacity for the convenient use of supply pipes of ample area is of particular importance in the case of large boilers, where each of the pipes N, NA, and NB 50 may need to be 20 feet in length or even longer, and must supply a correspondingly large amount of steam in the cleaning operation.

55 It will be apparent that the cleaning provisions disclosed permit the use of an ample number of nozzles and the uniform spacing of these nozzles along the end of each of the passes of the intertube space traversed by 60 the hot gases. Furthermore, the arrangement permits of the supply of an ample amount of the cleaning fluid to the various nozzles under uniform pressure conditions. It is therefore readily possible with the apparatus disclosed, to produce the relative

large volume and velocity of flow of the cleaning fluid discharged by the nozzles to the furnished gases set in motion thereby, required to rapidly and effectually sweep out of each pass from time to time the accumulations of soot, ashes and the like, constantly settling on the water tubes in the ordinary operation of the boiler and tending to materially decrease the boiler efficiency. It will also be apparent that in the construction disclosed all metallic portions of the cleaning apparatus are very effectually protected from high temperatures except in the case of the projecting tips of the nozzles O and O'. Should these exposed nozzles burn away, however, it is apparent that little damage will be done as the jets will still discharge through the holes of the cement body of the division walls which were originally filled by the burnt away nozzles.

35 The division walls H and I may be readily and comparatively inexpensively installed and are highly durable. In installing the division walls, the iron parts to be incorporated in the cement body portion are first put in place and then the cement material is applied in a plastic condition. The division wall construction disclosed obviously possesses advantages for use in boiler constructions regardless of whether or not cleaning provisions are incorporated therein. No claim is made herein, however, to this novel division wall construction except in combination with the cleaning provisions disclosed as the division wall construction itself is not my sole invention, but is the joint invention of William F. Sellers and myself, and is claimed in our co-pending application, Serial No. 719,512 filed of even date herewith.

100 It is, of course, apparent that the supply pipes may be arranged vertically or horizontally instead of obliquely where the spacing of the water tubes, or other conditions make such an arrangement necessary or desirable. One arrangement of employing horizontal supply pipes is shown in Figs. 5, 6 and 7. This arrangement incorporates other features differing from those in the constructions hereinbefore described, which 105 do not necessarily depend, however, upon the direction in which the supply pipes extend.

110 As shown in Figs. 5, 6 and 7, the division wall HA rising from the bridge wall GA, has incorporated in it two sets of nozzle supply pipes Q and Q', each provided with nozzles OA. The nozzles OA, connected to the pipes Q open from the front side of the division wall HA, while the nozzles connected to the pipes Q' open toward the rear of the 115 wall.

120 The pipes Q and Q' may well be and, as shown, are each formed in two sections, of which the one adjacent the closed end of the pipe is smaller in diameter than the other 130

section which supplies steam, or other cleaning fluid, both to the nozzles connected to it, and also to the nozzles connected to the smaller end of the pipe. Each of the pipes 5 Q and Q' is provided externally of the boiler housing, with an individual valve connection Q^2 to the vertical steam supply pipe R , and the latter is provided above the pipes Q and Q' with a supply valve R^1 , and below 10 the pipes with a drain valve R^2 .

In the operation of the apparatus shown 15 in Figs. 5, 6 and 7 the various individual valved connections Q^2 may be opened and closed successively. Any group of these 20 connections may be opened and closed at the same time.

While in accordance with the provisions 25 of the statutes, I have illustrated and described the best forms of my invention now known to me it will be apparent to those skilled in the art that changes may be made in the form of the apparatus disclosed without departing from the spirit of my invention, and that under some conditions certain 30 features of my invention may be used to advantage without a corresponding use of other features.

Having thus described my invention, what 35 I claim as new and desire to secure by Letters Patent, is—

1. In a water tube boiler, the combination 40 with a bank of water tubes and a transverse division wall which divides the intertube space into separate passes for the hot gases and comprises a body portion of non-metallic refractory material, of tube cleaning apparatus comprising a series of pipes embedded in said body portion and provided with nozzle outlets through which jets of a 45 cleaning fluid supplied to said pipes may be discharged into said intertube space in a direction parallel to said tubes.

2. In a water tube boiler, the combination 50 with a bank of water tubes and a transverse division wall which divides the intertube space into separate passes for the hot gases and comprises a body portion of non-metallic refractory material, of tube cleaning apparatus comprising a series of supply pipes embedded in said body portion and provided with nozzle branch pipes extending parallel to said tubes and opening to said 55 intertube space at one side of said division wall.

3. In a water tube boiler, the combination 60 with a bank of water tubes and a transverse division wall which divides the intertube space into separate passes for the hot gases and comprises a body portion of non-metallic refractory material and a metallic skeleton frame work, of tube cleaning apparatus comprising a series of pipes embedded in said body portion and secured to said skeleton frame work and provided with 65 nozzle outlets through which jets of a clean-

ing fluid supplied to said pipes may be discharged into said intertube space in a direction parallel to said tubes.

4. In a water tube boiler, the combination 70 with a bank of substantially parallel water tubes arranged in transverse rows, of a division wall dividing the intertube space into separate passes for the hot gases and comprising a body portion of refractory material and a skeleton frame work incorporated therein and comprising two transverse groups of metal bars arranged between the transverse rows of tubes, and tube cleaning provisions comprising pipes embedded in the body portion of said division wall between adjacent pairs of one of said groups of bars and having nozzle outlets through which jets of the cleaning fluid supplied to said pipes may be discharged into said intertube space in a direction parallel to the length of the water tubes.

5. In a water tube boiler, the combination 80 with a bank of parallel and substantially horizontal water tubes arranged in spaced apart rows inclined to the horizontal, of a tube cleaning apparatus comprising parallel pipes extending transversely to, and between the rows of water tubes and a horizontal supply pipe therefor extending across but external to, and having a lateral branch at one side of said bank of tubes, said inclined tubes being connected, each, to said supply pipe or to said branch, and having nozzle outlets opening into the space between the water tubes in a direction parallel to the lengths of said tubes.

6. In a water tube boiler, the combination 90 with a bank of parallel and substantially horizontal water tubes and a bridge wall beneath said bank of tubes, of a division wall rising from said bridge wall and dividing the intertube space into separate passes for the hot gases, of tube cleaning provisions comprising upwardly extending pipes embedded in said division wall and provided with nozzle outlets opening into the intertube space and adapted to discharge jets of a cleaning fluid into the intertube space in a direction parallel to the length of the water tubes, and a cleaning fluid supply pipe located beneath said bank of tubes on the cooler side of said bridge wall, and connections between said supply pipe and the lower ends of said upwardly extending tubes.

7. In a water tube boiler, the combination 100 with a bank of parallel and substantially horizontal water tubes arranged in spaced apart rows inclined to the horizontal, of a bridge wall beneath the bank of tubes, a division wall supported by said bridge wall and dividing the intertube space into separate passes for the hot gases, and tube cleaning provisions comprising a series of inclined tubes embedded in said division wall.

and arranged between inclined rows of the water tubes and provided with nozzle outlets adapted to discharge jets of a cleaning fluid into the space between the water tubes 5 in a direction parallel to the length of the latter, and a horizontal supply pipe located beneath the bank of tubes on the cooler side of said bridge wall and having a lateral branch located on the cooler side of said 10 division wall at one side of said bank of tubes, the lower ends of said tubes terminating at the bottom of said bank of water tubes being connected to said supply pipe and the lower ends of said tubes terminating at the side edge of said bank of water tubes 15 being connected to said branch.
